UNITED STATES PATENT OFFICE.

JOHN O. MORRIS, OF WASHINGTON, DISTRICT OF COLUMBIA, ASSIGNOR TO SOUTHERN STEMMING MACHINE AND MANUFACTURING COMPANY, OF GUTHRIE, OKLAHOMA, A CORPORATION OF OKLAHOMA.

TOBACCO-STEMMING MACHINE.

No. 888,835.

Specification of Letters Patent.

Patented May 26, 1908.

Application filed November 5, 1907. Serial No. 400,873.

To all whom it may concern:

Be it known that I, JOHN O. MORRIS, a citizen of the United States, residing at Washington, in the District of Columbia, have invented certain new and useful Improvements in Tobacco-Stemming Machines, of which the following is a specification, reference being had therein to the accompanying drawing.

10 This invention relates to improvements in tobacco stemming machines, the object of which is to mechanically strip the blade portions of the leaf from the stem in an expeditious and efficient manner.

15 In the accompanying drawings, Figure 1, is a perspective view of a mechanism embodying one form of my present invention. Fig. 2, is a top plan view of Fig. 1. Fig. 3, is a longitudinal, vertical, sectional view of the 20 receiving end of the stripping devices, when they are in their stripping positions. Fig. 4, is an enlarged, sectional view of the forward end of the stripping elements, shown in the leaf-receiving positions, and having the leaf- 25 carrier entering between them. Fig. 5, is a sectional, perspective view of the stripping devices, showing the leaf and its carrier in its position at the beginning of the stripping action. Fig. 6, is a similar view, but shows the 30 carrier drawing the leaf through the strippers, and the leaf being stripped from its stem. Fig. 7, is a vertical, longitudinal, central, sectional view of the receiving ends of the stripping devices. Fig. 7^a, is a detached 35 perspective view of the positioning device, looking from the outer side. Fig. 8, is a similar view, looking towards the inner side of the positioning device. Fig. 9, is a side elevation showing one form of mechanism 40 for imparting to the stripping devices an intermittent clearance movement. Fig. 10, is a transverse, sectional view of the machine shown in Fig. 1.

45 In carrying out my invention, I employ a stripping device which is composed of a plurality of closely - arranged stripping teeth, and a leaf-carrier which grasps the butt of the stem and draws the stem to and through the teeth while they are in a stationary strip- 50 ping position.

A suitable frame-work 1, has at its inlet end

a traveling feeding belt 2. The leaves are carried forward in this form of the machine, by the said belt to the point c (Fig. 3). At this point the butt ends of the leaves are 55 grasped by the traveling carriers a b and carried to the strippers d and e and enter between them when one of the strippers (here shown to be the one d) is separated from the other, as shown in Fig. 4. When the carriers reach 60 about the point shown in Fig. 5, the stripper is moved to its closed or stripping position shown in Figs. 3, 5 and 6. The carrier is moving all the while and carries the stem f through the teeth of the strippers, and the 65 spring or flexible teeth strip the blade portions g from the stem, which doubles up in front of the strippers substantially as illustrated at h, Fig. 6. The stripping occurs while the stripping teeth are held in a stationary stripping position, and against any effective stripping movement in a direction approaching or crossing the stripping path.

To prevent the stripped leaf portions h being carried into the strippers by the succeeding gripper, and destroyed, it is necessary that the stripped blade portions be removed from in front of the stripper before the following grippers reach the entrance point to the strippers. This may be accomplished 75 in many ways. In Fig. 1 it is accomplished by imparting to the stripping elements a clearing movement in a direction opposite to the movement of the leaf to be stripped, but this movement is not sufficient to effectively take part in the stripping action. In Fig. 9, the stripping devices are given an intermittent stripping movement, which takes place after the stripping action. Both of these movements are accomplished by mechanisms hereinafter described.

Stripping devices.—The stripping devices of my improved machine, as here shown are composed of flexible or yielding teeth arranged on an upper belt 4 which passes 95 around the roller 5 at its leaf-receiving end, and a roller 6, at its outlet end, and a lower belt 7 which passes around the rollers 8 and 9. These belts are provided with the closely arranged stripping teeth d and e. In Fig. 4, 100 these teeth are shown approximately full sized, and from which it will be observed that

they are long spring teeth. By reference to Fig. 5 it will be seen that the teeth on the upper belt project across and beyond the path of travel of the leaf stem *f*, while the 5 teeth in the lower belt project up about on a line with the said path and interlock with the upper teeth and serve to brace each other by engagement, as shown in Fig. 7.

The shaft of the roller 5 is journaled in 10 slotted standards 10, so that it may move up and down, and springs 11 serve to hold the roller down in the stripping position shown in Figs. 3, 5 and 6. It is moved up to the receiving position (Fig. 4) by means of the 15 cams 12, to let the carriers pass, and these cams are so shaped, arranged and timed in the operation of the machine, that they lift the front end of the stripper *d* when a carrier reaches it, (Fig. 4) and drop it suddenly 20 when the carrier reaches the position shown in Fig. 5. This position is preferably about in a vertical line with the axis of the roller 5. When the front end of the stripper drops, the spring and yielding teeth strike the 25 rounded upper surface of the carrier, and the teeth are projected to both sides thereof, as shown in Fig. 5. When the butt end of the stem is long the teeth at the front side of the carrier will project in front of the blades 30 of the leaf, but when the butt is short, or there is practically no projecting butt-end, the dropping of the teeth causes them to puncture and pass through the blade portions of the leaf, as shown in Fig. 5, and the 35 remaining blade portions are stripped from the stem. By using the belt strippers here shown the remaining ear portions of the leaf on the stem are removed by the teeth of the stripping belt, as the stem is being drawn 40 throughout the length of the belt, thus reclaiming or saving the "ear portions" of the leaf blades, and these reclaimed ear portions are finally delivered by the clearance movement of the strippers to the receiving ends 45 where they are removed by the upper and lower combs 14 and 15. These ear portions and the stripped blade portions are blown from the machine by a blast of air through the blower 3, and deposited below the ma- 50 chine.

The stripping belts or surfaces are widened out as shown, and the grippers are elongated to extend across them, which enables the grippers and the strippers to simultaneously 55 strip several leaves. The carriers or grippers *a b* are arranged on two upper traveling sprocket chains 16, which pass around the upper sprocket wheels 17, and upon the two lower traveling chains which pass around 60 the lower sprocket wheels 19. The members *a* of the carrier are attached to the upper chain 16 and the lower members *b* are attached to the lower chain 18, and they are arranged to meet about under the center of

the wheels 17 to grip the butt ends of the 65 stems. A stem-positioning device 20 is arranged at the gripping point, and against which the butt ends of the stems strike, and are held to be gripped and carried through the stripping devices. 70

The positioning device here shown consists of a separate device 22 for each leaf passage 21. These devices consist of depending members 22 capable of swinging inward and upward together to permit the carriers to 75 pass by them, but which have an independent return or rearward movement, and they are held in a vertical stem-positioning position by means of suitable springs 23. By having independently returnable positioning 80 devices, those devices which are not permitting the passage of a leaf will immediately return after the passage of the carrier and be in a position to catch any leaf that is passing forward to it. 85

A main shaft 24 is provided with pulleys 25 for a driving belt. A chain 26 passes around a wheel 27 on said shaft, and around a wheel 28 on the shaft 29 of the wheels 19, and the shafts 29 and 30 are provided with 90 meshing gears 31 and 32, and by this means the carrier chains 16 and 18 are revolved in unison. A suitable operative connection 33 connects the shaft 34 with the driving shaft 24, so that the shaft 34 is driven much slower 95 than the driving shaft, and the shaft 34 is belted or otherwise operatively connected with the rollers 5 and 8 of the stripping belts for driving the latter. As here shown, a straight belt 35 and a cross-belt 36 serve to 100 connect the shaft 34 and the rollers 5 and 8. This construction imparts to the strippers the slow leaf-clearing movement previously mentioned.

As shown in Fig. 1, the blower 3 extends 105 across the receiving end of the strippers, and it will be connected with any suitable device (not shown) for furnishing an air blast or a draft thereto. Preferably, in a machine of large capacity, (such as here shown) the 110 stripping belts or members are preferably divided into two parallel portions *A* and *B*, to enable the positioning of a center gripper-closing slideway *C* for the center of the carrier to prevent a separation of the jaws *a* and *b* thereof, and to enable the jaws to be made of thinner and lighter material, and still insure the gripping and holding of the butts of the stems. A chain 40 connects the cam shaft 41 with the shaft 42 of the lower carrier chain 18, and a chain 43 connects this latter shaft with the shaft 44 of the feed belt 2. 115

In Fig. 2, I show means for acting upon the blade portions at the butt ends of the 120 stems for subjecting the butt ends to an initial stripping operation. As here shown this device consists of two toothed rotating

members 50 which are geared together by gears 51, and driven by a belt 52 passing around a pulley 53. Preferably, the toothed rolls have the lower one arranged somewhat 5 in advance of the upper one.

In operation, the person feeding the machine will take a bunch of the leaves and push the butt ends of the bunch between these rollers and hold the bunch in his hand. 10 The rapid rotating rolls instantly act upon the blades and butt ends of the stems, and any remaining blade portions will be removed by the elongated stripping surfaces of the stripper, as previously described. The 15 operator places the leaves to be stripped in a separated position, either upon the table 54 (Fig. 2) or upon the feeder-belt 2 (Fig. 1). When placed on the table 54 the butt ends of the stems are pushed against the positioning 20 device to be in position to be grasped by the carriers.

In Fig. 9 I show one form of means by which the stripping teeth may be given an intermittent clearance movement occurring 25 after the stripping action is effected. This form consists in providing the mechanism with a wrist-pin 55 adapted to engage a finger 56 upon a pitman or rod 57. The opposite end of this rod 57 is pivotally connected 30 with an intermediately-pivoted lever 58 which has pivoted to opposite ends the ratchet bars 59 and 60. The ratchet bar 59 is adapted to engage a ratchet 61 on the upper roll of the stripping device, and the 35 bar 60 to engage a ratchet 62 on the lower roll 8 of the stripping device. Suitable springs 63 and 64 engage respectively the ratchet bars 59 and 60 and serve to hold 40 them in engagement with the ratchet wheels 61 and 62 when they are actuated in a direction to rotate said wheels, but will permit the bars to ride over the ratchets when they are moved in the opposite direction. A spring 45 serves to hold the rod 57 in proper position to have the pin 55 engage it. In operation, the pin 55 engages the finger 56 and draws the bar 57 until the pin passes out of the path of the finger, when the spring 65 will draw the parts to the position shown in Fig. 9. 50 A suitable buffer of rubber or other suitable material, such as 66, is used to stop the parts when they are drawn back by the spring 65. The amount of movement given to the parts just described can be regulated in any suitable way, such for instance, as either making the buffer 66 adjustable as here shown, or by making the finger 56 adjustable upon the rod 57.

The term stationary as employed in the 60 claims, is applicable in the sense that the effective or active teeth have a stationary stripping position relative to any movement into or out of the stripping plane.

Having thus described my invention, what

I claim and desire to secure by Letters Patent, is:—

1. In a tobacco stemmer, the combination with stripping elements comprising closely-assembled stripping teeth, and a leaf holder, of means imparting a relative movement to 70 said elements to strip the blade from the stem of the leaf while the effective teeth are substantially held against a movement in a direction approaching the plane of the relative stripping movement of said elements. 75

2. In a tobacco stemmer, the combination with stripping elements comprising a plurality of laterally-yielding stripping teeth, and a leaf holder, of means imparting a relative movement to said elements to strip the 80 blade from the stem of the leaf while the effective teeth are substantially held against a movement in a direction approaching the plane of the relative stripping movement of said elements. 85

3. The combination in a tobacco stemmer having a stripping path, of stripping elements comprising a leaf holder, a plurality of closely-arranged stripping teeth extending across said stripping path, and means imparting a relative movement to said elements in a direction transverse said teeth to strip the blades from the stem of the leaf while the teeth are substantially held against a movement approaching the plane of the 95 relative stripping movement of said elements. 90

4. In a tobacco stemmer, the combination of stripping elements comprising a plurality of closely-arranged stripping teeth, a leaf 100 holder, and means imparting to said elements a relative stripping movement longitudinal the leaf at a speed requisite to strip the blade of the leaf from the stem, the effective teeth being held from movement in a direction 105 transverse the leaf during said stripping movement.

5. In a tobacco stemmer, the combination of a plurality of closely-arranged laterally-yielding effective stripping teeth maintained 110 relatively stationary to any movement in a direction across the stripping path at the stripping point, a leaf holder, and means imparting to said elements a relative stripping movement of the stripping point in a direction transverse said teeth. 115

6. In a tobacco stemmer, the combination of stripping elements comprising a plurality of closely-assembled stripping teeth, a leaf holder, and means imparting to said elements 120 a relative stripping movement to strip the blade from the stem of the leaf while the effective teeth are held against a movement in a direction approaching the plane of relative movement of said elements, and means for 125 imparting a clearance action to said teeth.

7. In a tobacco stemmer, the combination of stripping elements comprising a plurality

- of stripping teeth held in a fixed plane and against any relative rotary stripping movement at the stripping point, a leaf holder, and means imparting to said elements a stripping movement longitudinal the leaf to be stripped.
8. In a tobacco stemmer, the combination of stripping elements comprising a plurality of closely-arranged laterally yielding stripping teeth held against any relative rotary stripping movement at the stripping point, a leaf holder, and means imparting to said elements a relative stripping movement longitudinal the leaf to be stripped.
15. The combination in a tobacco stemmer, of a plurality of closely-arranged stripping teeth having a stationary stripping position, means for moving a leaf to and against the teeth to be stripped thereby, and means engaging and moving the stripped leaf portions away from the stripping teeth for the purpose described.
10. The combination in a tobacco stemmer, of a plurality of closely-arranged stripping teeth held in a stationary stripping position during the stripping action, and means imparting to the teeth a succeeding stripped leaf clearance action.
11. The combination in a tobacco stemmer, of a plurality of closely-arranged yielding stripping teeth, means for moving a leaf butt foremost in a stripping path, means holding the stripping teeth first in a position out of the stripping path, and then to a stationary stripping position across the stripping path immediately back of the butt end of the leaf stem.
12. In a tobacco stemmer, a stripping device comprising a plurality of closely-arranged stripping teeth held in a stationary stripping position extending in a direction across and beyond the stripping path during the stripping operation, and a plurality of co-acting teeth held stationary during the stripping operation and extending in the opposite direction and having their extremities about in a line with the stripping path.
13. In a tobacco stemmer, the combination of a plurality of closely-arranged stripping teeth held in a stationary stripping position across the leaf path, said plurality of teeth occupying a space elongated relative to the path of the leaf and acting to first remove the main leaf portions from the stem, and then to remove any remaining ear portions from the stem.
14. The combination in a tobacco stemmer, of a stripping device comprising a belt extending parallel to the leaf path, and having a plurality of laterally-extending closely-arranged stripping teeth, held in a stationary position across the leaf path, and means for carrying a stem endwise therethrough for first stripping the main portions of the leaf from the stem and afterwards removing any remaining portions of the leaf therefrom.
15. The combination in a tobacco stemmer, of a stripping device comprising parallel belts located at opposite sides of the leaf path, the belts having oppositely-extending teeth, the belts and their teeth held in a stationary stripping position, and means for carrying a leaf in a direction between said belts and subjecting it to the stripping action of the said stationary teeth.
16. The combination in a tobacco stemmer, of a belt having a plurality of closely-arranged stripping teeth which extend in a direction across the path of the leaf to be stripped and held during the stripping action in a stationary stripping position, and means for imparting to the belt a succeeding stripped leaf clearance action for the purpose described.
17. The combination in a tobacco stemmer, of two separated stripping devices extending longitudinal the stripping path and arranged side by side, a leaf gripper extending transverse the machine and spanning both of said stripping devices, and an elongated gripper support extending longitudinally between said stripping surfaces.
18. In a tobacco stemmer, the combination of a plurality of stripping teeth held in a stationary stripping position during the stripping action, means for carrying the leaf butt end foremost against the teeth and the stem portion between the teeth, and means for imparting to the stripping teeth a clearing movement after the stripping action.
19. In a tobacco stemmer, the combination of a plurality of closely-arranged yielding stripping teeth held in a stationary stripping position during the stripping operation, means for subjecting the leaf to the action of the stripping teeth while the stripping teeth while they are stationary, and means for imparting a clearing movement to the stripping teeth after the stripping action.
20. In a tobacco stemmer, the combination of a plurality of stripping teeth held in a stationary stripping position, during the stripping operation, means for subjecting the leaf to the action of the stripping teeth while they are in the stripping position, and an intermittently-operating mechanism constructed to impart to the stripping teeth a leaf-clearing movement after the stripping operation.
21. In a tobacco stemmer, the combination with a plurality of stripping teeth held in a stationary stripping position during the stripping operation, and a leaf carrier, of means for preliminarily stripping the stem leaf butt portions from the butt end of the stem in advance of the stripping operation.
22. In a tobacco stemmer, the combination of a plurality of closely-arranged strip-

ping teeth held in a stationary stripping position during the stripping action, a device in advance of the stripping teeth adapted to position the butt ends of the stem, and a leaf carrier adapted to grasp the butt ends of the stems and carry them between the stripping teeth while the latter are in their stationary stripping position.

23. In a tobacco stemmer, the combination of two parallelly arranged stripping surfaces composed of closely-arranged oppositely-extending stripping teeth, the inlet

portions of the stripping surfaces being curved in opposite directions, the teeth being held in a stationary stripping position during the stripping action, and means for carrying the leaves butt end foremost to the curved portions of the stripping surfaces.

In testimony whereof I affix my signature in presence of two witnesses.

JOHN O. MORRIS.

Witnesses:

JOHN L. FLETCHER,
